UNITED STATES PATENT OFFICE

JOHN W. FREE, OF ALIQUIPPA, PENNSYLVANIA, ASSIGNOR TO JONES & LAUGHLIN STEEL CORPORATION, OF PITTSBURGH, PENNSYLVANIA, A CORPORATION OF PENNSYLVANIA

SKELP FORMING MACHINE

Application filed August 30, 1929. Serial No. 389,374.

My invention relates to the manufacture of pipe and, in particular, to the cold forming of skelp for the manufacture of pipe, as by the flash welding method.

5 A present preferred embodiment of my invention is illustrated in the accompanying drawings in which:

Figure 1 is a partial side elevation of the skelp forming machine of my invention;

10 Figure 2 is a transverse sectional view of the machine taken along line II—II of Figure 1; and

15 Figure 3 is a view similar to Figure 2 except that it illustrates only a portion of the latter on an enlarged scale.

Referring to the drawings, my skelp forming machine comprises a frame made up of a plurality of structural members 10 which are secured together by means of tie rods 11 20 in spaced relation maintained by a spacing structure 12. As it will appear from Figure 2, there are two of the frame members 10 on each side of the machine.

The frame members 10 are maintained in 25 spaced relation laterally by means of structural members 13. The lower frame members 10 are supported on suitable foundations 14.

30 A cylindrical mandrel 15 is supported within the frame formed by the members 10. The mandrel 15 is not continuous but consists of a number of sections each mounted on suitable supports 16.

35 A plurality of bridging members 17 connect the lower portions of the upper frame members 10 and provide bearings 17a for the bending jaws 18 journaled therein. The bending jaws 18 consist of jaw members 19 of 40 a length corresponding to that of the sections of the mandrel 15. A plurality of pivoted arms 20 journaled in the member 17 afford means for actuating the jaw members 19.

45 Frame members 21 are disposed at a plurality of points along the top of the upper frame members 10 to afford a support for the cylinders 22. Suitable pistons are disposed in the cylinders 22 and provided with 50 cross heads 23. Compression links 24 con-

nect the crossheads 23 with the pivoted arms 20 of the bending jaws 18.

On one side of the skelp forming machine a supporting table 25 is arranged for receiving a supply of unformed skelp. The supporting table 25 embodies means for advancing a strip of skelp from the table to the mandrel 15. This means comprises a plurality of push rods similar to that shown at 55 26 and any suitable means such as the rack 50 and pinion 27 and 28 for actuating the push rods. The pinions 28 are mounted on a shaft 29 which may be driven from any convenient driving means.

I provide means in the form of a balancing 65 finger 30 for maintaining a flat skelp in proper position on the mandrel 15 preparatory to an operation of the bending jaws 18. The balancing finger 30 is pivoted on a lug 31 and is adapted to be operated by a fluid 70 pressure cylinder and a piston 32. In addition to the balancing finger 30, I may make use of a clamping bar 33 which may be operated by means similar to those shown for operating the finger 30. It will be obvious 75 that the balancing finger 30 makes possible the proper positioning of a flat strip of skelp on the mandrel 15 and that the clamping rod 33 serves to maintain the skelp on the mandrel during the operation of the bending jaws. 80

After the skelp has been positioned on the mandrel 15, the bending jaws 18 may be operated by admitting fluid under pressure to the cylinder 22, whereupon the jaws descend, engage the edges of the skelp and bend it to 85 the form of the mandrel 15. Because of the slight tendency of the formed skelp to spring away from the die 15 when the bending jaws are retracted, I make the die slightly smaller 90 in diameter than the size of the finished pipe. 90

By reason of the location of the bearings 17a of the bending jaws 18, the jaws members 19 bend the skelp merely by pressing the edges thereof down around the mandrel 15. There is very little abrasion of the jaw members 95 by the edges of the skelp. The jaw members are removable from the jaws so that the former may be replaced when they become worn as a result of the slight abrading action which can not be avoided. 100

A number of levers 34 are fixed to a shaft 35. The levers lie between adjacent sections of the mandrel 15 below the edges of the formed skelp. A fluid pressure cylinder and piston 36 and a crank 37 are provided for operation of the levers 34. After the skelp has been formed the admission of fluid under pressure to the cylinder 36 will rock the levers 34 and the shaft 35 to lift the half section of formed skelp from the mandrel 15 so that it slides down upon the receiving table 38 from which it is passed through the welding machine. As appears in Figure 1, the levers 34 are fixed on the shaft 35, distributed along the length of the skelp and positioned between the adjacent sections of the mandrel 15.

Numerous advantages of my invention will be obvious to those skilled in the art. This invention makes possible the rapid forming of flat skelp into semi-cylindrical shape. The operation of the machine is simple and easy to control and the product is uniform in shape. All the advantages of cold bending process for forming skelp are inherent in this invention.

Although I have described but a single preferred embodiment of my invention, it is not my intention to be limited thereto as the scope of my invention is defined by the appended claims.

I claim:

1. In a skelp-forming machine, upper and lower longitudinal frame members, and means for maintaining a spaced relation therebetween, a cylindrical die supported horizontally on said lower frame members, means including push rods and a balancing finger for positioning a strip of skelp on said die, means for holding it thereon, forming means for bending said skelp around said die including arms pivoted at each side of said upper frame member for engaging the edge of the skelp on the other side of the die, and a fluid-operated piston for actuating said arms.

2. In a skelp-forming machine, a frame, a cylindrical die supported horizontally in said frame, means for placing a flat strip of skelp on said die and holding it thereon, bending arms journaled in said frame, means for actuating said arms into engagement with the edges of said skelp to bend it around said die, and a pivoted arm for removing the formed skelp from the die.

3. A skelp-former comprising a frame, a cylindrical die supported therein, means for supporting flat strips of skelp adjacent said die, means for removing said strips successively from said supporting means onto said die and means for maintaining the strips thereon, bending jaws at each side of said frame for engaging the edge of said skelp opposite to the side of the frame on which the jaws are pivoted, means for actuating the jaws to bend the skelp around the die and

means for removing the formed skelp therefrom when said jaws have been withdrawn.

4. The combination with a mandrel, means for supporting a metal strip thereon and jaws for bending it around said mandrel, said mandrel being of smaller size than that of the desired bent strip, whereby the inherent tendency of the latter to spring is compensated, of laterally movable arms for removing the strip from the mandrel.

5. The combination with a cylindrical die and bending means for shaping plates thereover, of pivotally mounted, independently retractable balancing means for maintaining plates on the die in position to be engaged by said bending means.

6. In a skelp-forming machine, the combination with a cylindrical die, means for placing a flap strip of skelp on the die and balancing it thereon, pivoted bending jaws for engaging the edges of said skelp and bending it around said die, means for actuating said jaws and means for removing the formed skelp laterally from said die.

7. A skelp-former comprising a die for forming a strip of skelp, means for feeding skelp to the die and holding it thereon, pivoted jaws for cooperating with said die, actuating means for the jaws, and means for removing formed skelp laterally from said die.

8. In a skelp-forming machine, the combination with a cylindrical die, a supporting frame, means for associating a flat strip of skelp therewith, pivoted bending jaws for engaging the edges of said skelp and bending it around said die, means for actuating said jaws and means for removing the formed skelp laterally from said die, said bending jaws being pivoted to said supporting frame at points on opposite sides of the die from those engaged by the jaws.

In testimony whereof I have hereunto set my hand.

JOHN W. FREE.
